(57) **CLAIM**

We claim the ornamental design for a golf club head, as shown and described.

DESCRIPTION

FIG. 1 is a perspective view of a golf club head, as viewed from the rear, below and one side, according to one embodiment.

FIG. 2 is a front elevation view of the golf club head of FIG. 1.

FIG. 3 is a rear elevation view of the golf club head of FIG. 1.

FIG. 4 is a side elevation view of a toe side of the golf club head of FIG. 1.

FIG. 5 is a side elevation view of an opposite heel side of the golf club head of FIG. 1.

FIG. 6 is a top plan view of the golf club head of FIG. 1.

FIG. 7 is a bottom plan view of the golf club head of FIG. 1; and,

FIG. 8 is a cross-sectional view taken along line 8-8 of FIG. 7 of a midsection of a slot formed in the outer surface of the sole of the golf club head of FIG. 1.

The dashed lines in the drawings are for illustrative purposes only and form no part of the claimed design.

1 Claim, 5 Drawing Sheets
